UNITED STATES PATENT OFFICE.

FREEMAN CASS, OF BROOKLYN, NEW YORK.

THREAD GUIDE FOR TEXTILE MACHINES.

Application filed February 28, 1922. Serial No. 539,944.

To all whom it may concern:

Be it known that I, FREEMAN CASS, a citizen of the United States, residing at Brooklyn, Kings County, State of New York, have invented certain new and useful Improvements in Thread Guides for Textile Machines, of which the following is a specification.

This invention relates to thread guides for textile machines.

Guides of this class as heretofore constructed are formed with an eye having curved walls or more or less rounded corners, the result being that any knots on the thread are permitted to pass through the guide and into the other parts of the machine. The object of this invention is to provide a guide having the walls of the eye arranged so as to form angles or sharp V-shaped corners in the eye so that whenever knots or slugs occur in the silk thread passing through the guide they will be caught by the guide and the silk broken down. A guide such as that of the present invention will, to a considerable extent, prevent the passage of knots on the thread.

In the accompanying drawing there is illustrated in elevation and partly in section a thread guide embodying the present invention.

The guide, as shown in the drawing, comprises a body 10, provided at its lower end with a recess or socket 11 in which a supporting wire 12 is secured. The upper portion of the body is provided with an elongated eye 13 which comprises an upper portion 14 and a lower portion 15 which are connected by a narrow passageway 16. An inlet slot 17 extends upwardly and inwardly and communicates with the lower portion 15 of the eye. The rear wall 18 of the eye 13 or in other words the wall opposite the inlet slot 17 is preferably made straight and arranged substantially vertically. The upper wall 19 of the upper portion of the eye is arranged at an acute angle to the wall 18 whereby a sharp V-shaped corner is formed at the point 20 in the upper portion of the eye. The bottom wall 21 of the lower portion of the eye is also arranged at an acute angle to the wall 18 whereby there is formed a sharp V-shaped corner 22 at the bottom of the lower eye. The wall 19, it will be observed, extends forwardly and downwardly while the wall 21 extends forwardly and upwardly. The upper portion of the eye is

also provided with a wall 23 which is arranged at an angle with the wall 19 whereby a second sharp corner 24 is provided in the upper portion of the eye. The material of the body 10 above the slot 17 extends toward the vertical wall 18 to provide the narrow passage way 16 heretofore described.

In the operation of the device the thread normally rests in the upper eye and in passing through the same will naturally lie in one of the sharp corners of this portion of the eye. The result is that any knots in the thread will be caught as the thread passes through the eye. In case the thread, due to vibration of the same, drops out of the upper portion of the eye it will be caught by the lower portion thereof and will then normally lie in the sharp corner 22 of the lower portion of the eye.

What I claim as my invention and desire to secure by Letters Patent is:

1. A thread guide for textile machines comprising a body having an eye provided with a substantially straight rear wall, said eye consisting of an upper portion and a lower portion with a narrow passageway connecting the same, the upper wall of said upper portion and the lower wall of said lower portion of the eye being arranged at an acute angle to said rear wall, whereby a sharp corner is formed at the top and bottom of said eye, and an inlet slot communicating with said lower portion of the eye opposite said rear wall.

2. A thread guide for textile machines comprising a body having an eye provided with a substantially straight rear wall, that portion of the body in front of the eye being provided with a part extending rearwardly into close proximity to said rear wall whereby said eye is divided into an upper portion and a lower portion with a narrow passage connecting the same, the upper wall of said upper portion of the eye and the lower wall of said lower portion of the eye each being arranged at an acute angle to said rear wall, whereby a sharp corner is formed at the top and bottom of said eye, said body having an inlet slot communicating with said lower portion of the eye above the lower end of said rear wall, the upper wall of said inlet slot being inclined downwardly and outwardly from said narrow passage to the front edge of said body substantially as described.

FREEMAN CASS.
